(57) **CLAIM**

The ornamental design for a wearable gear holder, as shown
and described.

DESCRIPTION

FIG. 1 is a perspective view of a wearable gear holder in
accordance with my invention;

FIG. 2 is a top view thereof;

FIG. 3 is a bottom view thereof;

FIG. 4 is a side view thereof;

FIG. 5 is an opposite side view thereof;

FIG. 6 is a front view thereof;

FIG. 7 is a back view thereof with the back plate removed
for clarity of illustration;

FIG. 8 is a back view of the wearable gear holder of FIG. 1;
and,

FIG. 9 is a perspective view thereof shown in environmental
use.

The broken lines shown represent unclaimed subject matter
and form no part of the claimed design.
